(57) **CLAIM**

The ornamental design for a multipurpose hand tool with folding pliers, as shown and described.

DESCRIPTION

FIG. 1 is an isometric view from the upper right front of a multipurpose hand tool with folding pliers including our new design, wherein heads of pivot pins and portions of a blade latch mechanism shown in broken line are included merely for illustrative purposes and form no part of the claimed design;

FIG. 2 is a right side elevational view thereof, wherein heads of pivot pins and portions of a blade latch mechanism shown in broken line are included merely for illustrative purposes and form no part of the claimed design;

FIG. 3 is a left side elevational view thereof, wherein the heads of pivot pins and portions of a blade latch mechanism shown in broken line are included merely for illustrative purposes and form no part of the claimed design;

FIG. 4 is a top plan view thereof, a bottom plan view thereof being identical thereto, wherein a portion of a pivot pin shown in broken line is included merely for illustrative purposes and forms no part of the claimed design;

FIG. 5 is a rear end elevational view thereof, wherein portions of pivot pins and of blade latch mechanisms shown in broken line are included merely for illustrative purposes and form no part of the claimed design; and,

FIG. 6 is a front end elevational view thereof, wherein portions of pivot pins shown in broken line are included merely for illustrative purposes and form no part of the claimed design.
